UNITED STATES PATENT OFFICE.

GEORGE W. KNIGHT, OF NEW YORK, N. Y.

COMPRESSOR OR ABDOMINAL SUPPORTER.

1,119,614.

Specification of Letters Patent.

Patented Dec. 1, 1914.

Application filed October 21, 1913. Serial No. 796,465.

To all whom it may concern:

Be it known that I, GEORGE W. KNIGHT, a citizen of the United States, and a resident of the city of New York, borough of the Bronx, in the county and State of New York, have invented a new and Improved Compressor or Abdominal Supporter, of which the following is a full, clear, and exact description.

10 This invention relates to abdominal supports of that type comprising a band that encircles the abdominal portion of the body to perform the usual functions of this type of support.

15 The invention has for its general objects to improve and simplify the construction of abdominal supports so as to accomplish the purposes for which it is applied, and at the same time permit of being easily and 20 quickly attached or detached and while in place be comfortable to the wearer in the natural movements of the body, as in changing from a sitting to a standing posture, or vice versa, or in the lateral bending of the 25 body.

Another object of the invention is the provision of an abdominal support or band which includes the abdominal pad or section which is flexibly attached to the body or 30 major or side portion of the band so that the wearer can freely move with comfort and a minimum displacement of the abdominal section.

Another object is the provision of apertures in the band corresponding to the upper and prominent portions of the hip bones and anatomically known as the crest of the ilii, such apertures being covered with insertions of flexible mesh material, such apertures and insertions adding to the comfort of the wearer by reducing friction and chafing, as well as contributing toward holding the band effectively in place.

Still another object of the invention is 45 the provision of a novel form of perineal straps supplied to prevent the band from riding upward, said straps or bands being attached to the lower part of the abdominal pad or front section, passing thence downward, backward and upward and terminating in a bifurcated extremity attached to the rear and side of the belt in such a manner and at such points as to balance and equalize the traction thereon in the sitting 50 or standing position of the wearer, at the

same time holding the belt firmly against the lower abdomen in front.

With such objects in view, and others which will appear as the description proceeds, the invention comprises various novel 60 features of construction and arrangement of parts which will be set forth with particularity in the following description and claims appended hereto.

In the drawings, which illustrate one 65 embodiment of the invention, and wherein similar reference characters are employed to designate corresponding parts in all the views, Figure 1 is a side view of the band applied to the body and showing the manner 70 in which the perineal straps operate while the wearer is standing; Fig. 2 is a side view of the band with the wearer in a sitting position; Fig. 3 is a rear view of the band applied; Fig. 4 is a perspective view of the 75 abdominal supporter; Fig. 5 is a plan view; and Fig. 6 is a view of the front section or abdominal pad of the band.

Referring to the drawing, A designates the front section or abdominal pad of the 80 supporter and B the body or major section of the supporter, such major section being made in two parts b, b', which are secured together at the rear of the band by a lacing 85 1 after the fashion of corsets, whereby the band can be more readily fitted to the wearer. The body section B of the supporter or band extends around the waist portion of the wearer from the rear forwardly to a point slightly in front of the 90 hip bones, and the abdominal pad A bridges the gap between the ends 2 and 3 of the body section B. The ends 4 and 5 of the section A underlie the ends 2 and 3, and the two sections are fastened together by a series of straps 6 and 7 on the section A, and buckles 8 and 9 on the ends of the body B. These straps serve not only as means for enlarging or reducing the size of the abdominal band or support, but also flexibly attaching the abdominal pad to the body so 100 that the wearer can readily move, that is to say, bend forwardly or laterally, without undue restriction. The straps 7 are of sufficient length that the abdominal band can be loosened, as shown by dotted lines in Fig. 5, to allow the band to be detached by passing downwardly off the legs of the wearer.

In applying the band it will be open to its full extent, as shown by dotted lines, and 110

then slipped upwardly over the legs and adjusted to the body, the tightening of the band being performed at the front. This is a special advantage, particularly when a person must lie flat on the back in order to throw the abdominal contents in the proper position for the application of the abdominal support.

At the sides of the band, and particularly adjacent the ends of the body B, are means whereby the band can conform closely to the shape of the hip bones, thereby contributing in holding the supporter effectively in place. The body B, like the abdominal pad A, is made of strong material, such as canvas, and this canvas has openings 9^a adjacent the ends of the body B of the band, and applied to the openings by sewing or otherwise are insertions of flexible material 10, such as mesh material. These iliac insertions fit snugly over the upper portions of the hip bones, which slightly protrude through the band, as clearly shown in Fig. 3. In order to bring the ilium-engaging portions of the band in the right position the parts b, b' of the body B can be adjusted by tightening or loosening the lacing 1.

To hold the abdominal pad A properly in place a pair of perineal straps C are employed. These straps have their front ends secured to the bottom portion of the pad A close to the middle thereof, where buckles 11^a are provided. These straps extend downwardly so as to pass between the legs, and thence rearwardly and upwardly where they are formed into bifurcations 11 and 12, which are respectively fastened to the lower edges of the body B at points under the iliac insertions 10 and to the rear thereof. By forming the rear portions of the straps C into forks and attaching the forks to the body B in the manner shown, the straps will be constantly maintained under tension, so that the band will not ride upward and the bottom of the abdominal pad A will be held tightly against the abdomen irrespective of the position of the wearer. Thus, when the wearer is in standing position, as shown in Figs. 1 and 3, it will be obvious that the members 11 of the perineal straps are under tension, while the members 12 are loose, whereas the members 12 are taut and the members 11 loose when the wearer is in sitting position. The straps C are preferably made of woven tape so as to always lie flat against the body. The two sections A and B of the supporter or band are preferably formed inside with a soft absorbent lining of mesh material 13 secured to the inner faces of the sections by stitching or any other suitable means. The abdominal pad A is preferably stiffened by vertical ribs 14 set in between the plies of the fabric of

which the pad is made, and the ends of the parts b, b' of the body B are provided with vertical stiffening ribs 15, as indicated by the dotted lines, Figs. 1 to 3 inclusive.

From the foregoing description taken in connection with the accompanying drawings, the advantages of the construction and method of operation will be readily understood by those skilled in the art to which the invention appertains, and while I have described the principle of operation, together with the appliance which I now consider to be the best embodiment thereof, I desire to have it understood that the appliance shown is merely illustrative, and that such changes may be made when desired as are within the scope of the appended claims.

Having thus described my invention, I claim as new and desire to secure by Letters Patent:

1. An abdominal supporter comprising a body section adapted to extend around the back and sides of the wearer and including flexible pieces overlying the iliac regions of the wearer's body, said body section being composed of adjustably connected parts for lengthening or shortening the body section to adjust said flexible pieces to the iliac regions of the wearer's body, an abdominal pad section having its ends flexibly and adjustably connected with the ends of the body section, and perineal straps having their front ends connected with the abdominal pad section and divided at their rear extremities into bifurcations connected respectively to the body section at points under the portions that engage the ilia and to the rear thereof, one bifurcation being taut and the other loose when the wearer is in a sitting position, and vice versa when the body is in a bent position, whereby at all times a downward tension is maintained on both sections of the band.

2. An abdominal supporter comprising a body adapted to extend around the back and sides of the wearer and having openings in its iliac regions, and flexible pieces inserted in the openings; an abdominal pad having its ends flexibly and adjustably connected with the ends of the body; and perineal straps having their front ends connected with the bottom portion of the abdominal pad and having bifurcations at their rear extremities, connected respectively to the body at points below the said openings and to the rear thereof.

In testimony whereof I have signed my name to this specification in the presence of two subscribing witnesses.

GEORGE W. KNIGHT.
